UNITED STATES PATENT OFFICE.

DAVID BRANDT, OF NEW YORK, N. Y.

RECEPTACLE FOR PARING-MACHINES.

1,287,856.

Specification of Letters Patent. Patented Dec. 17, 1918.

Application filed February 15, 1918. Serial No. 217,296.

To all whom it may concern:

Be it known that I, DAVID BRANDT, a subject of the Emperor of Austria, residing at New York, county of Bronx and State of New York, have invented new and useful Improvements in Receptacles for Paring-Machines, of which the following is a specification.

This invention relates essentially to a device adapted for connection with a vegetable paring machine, and it comprehends a container provided with a wire netting receptacle for receiving the peels and waste matter scraped or abraded from the vegetables.

The invention is designed to provide means for leading the waste liquid mixed with the peels from the paring machine to the container and into the foraminated receptacle from which the liquid is drawn off, and the parings or heavy matter remain.

The novel features of the invention are more fully described in the following specification and claims and illustrated in the accompanying drawing in which:

Figure 1 represents a sectional side elevation showing the container connected to a paring machine.

Fig. 2 is a vertical section of the container.

Fig. 3 is a side elevation of the wire receptacle.

Fig. 4 is a similar view of the receptacle looking in the opposite direction.

In this drawing is shown a vegetable paring machine having a cylinder 5 with a water inlet 6 and a plate 7 arranged in the cylinder. The plate is provided with a top abraded or rough surface, and rotary motion is transmitted to the plate by means of an electric motor 8 secured to the machine. The vegetables when scoured of their coats by the rotation of the plate, can be transferred from the cylinder by a chute 9 controlled by a gate 10 slidably mounted on the wall of the cylinder; the foregoing parts of the machine are well known and need no further description.

The container 11 has a cover 12 and is equipped with an inlet pipe 13 leading into the upper portion of the container. This pipe is connected to the cylinder 5 and when a valve 14 is opened, the parings from the vegetables and the waste liquid will flow into the container. A pipe 15 governed by a valve 16 leads the waste liquid from the container. This pipe can be connected to a drain or sewer for leading off the foul water.

In the container is arranged a wire receptacle or cage 17 having a handle 18 for lifting the receptacle out of the container. At the upper part of the side portion of the wire receptacle is located an elongated opening 19. By placing the opening adjacent to the inlet pipe 13 the refuse from the cylinder is dropped into the wire receptacle. The side wall 20 of the wire receptacle opposite the opening is depressed so as to form a space 21 between the wall of the outer container and the wire receptacle. The other walls of the wire receptacle fit snugly into the container.

The space 21 between the container and receptacle permits any of the liquid in the receptacle to be drawn off through the outlet pipe. The sides and top of the receptacle are constructed of somewhat fine wire mesh with small interstices, so that the light liquid will flow off continuously through the outlet pipe, and the heavy residue of peelings mixed with liquid will remain in the receptacle and clogging of the drain pipe is eliminated. As indicated in the drawing, the bottom of the wire receptacle has slightly larger perforations than the other walls, so that while the receptacle is lifted out the thick liquid will flow into the container and can be flushed off through the outlet or otherwise. The heavy particles of matter such as the parings remaining in the wire receptacle can be dumped out through the elongated opening. The perforated receptacle 17 constitutes a portable cage having bottom, top and side walls wholly inclosing the receptacle. This receptacle can be lifted out of the container 11 by removing the cover 12 and the contents remaining in the receptacle are poured out of the elongated opening. It will be seen that when the receptacle is slid into the container 17, the outer rim adjacent to the depressed wall will contact with the inner side of the container to give the receptacle a snug fit.

I claim:

1. A receptacle comprising a container having a cover, an inlet and an outlet pipe connected to the container; combined with a perforated portable cage including a top, bottom and sides to slidably fit into the container, one of the sides having an elongated opening adjacent to the inlet, and a depressed side opposite the opening to form a space at the outlet.

2. A receptacle comprising a container

having a cover, an inlet and an outlet pipe connected to the container; combined with a wholly inclosed perforated cage, including a top with means for lifting the cage from the container, one of the sides having an elongated opening adjacent to the inlet, and a depressed side opposite the opening to form a space at the outlet.

3. A receptacle comprising a container having a cover, an inlet and an outlet pipe connected to the container; combined with a wholly inclosed perforated cage, including a top with means for lifting the cage from

the container, one of the sides having an elongated opening adjacent to the inlet, a 15 depressed side opposite the opening to form a space at the outlet, and a rim contiguous to the depression to slidingly coat with the inner side of the container.

In testimony whereof I have hereunto set 20 my hand in the presence of two subscribing witnesses.

DAVID BRANDT.

Witnesses:

GRACE DE VOE,
WILLIAM MILLER.
